UNITED STATES PATENT OFFICE.

ASAHEL M. SHURTLEFF, OF BOSTON, MASSACHUSETTS.

DESIGN FOR A CAP AND NOZZLE FOR ATOMIZERS.

SPECIFICATION forming part of Design No. 21,148, dated November 3, 1891.

Application filed November 24, 1890. Serial No. 372,534. Term of patent 14 years.

To all whom it may concern:

Be it known that I, ASAHEL M. SHURTLEFF, a citizen of the United States, residing at Boston, in the county of Suffolk, State of Massachusetts, have invented and produced a new and original Design for a Cap and Nozzle for Atomizers, of which the following is a specification, reference being had to the accompanying drawings, forming a part thereof.

Figure 1 shows in elevation a cap and nozzle for atomizers showing my design; Fig. 2, a vertical section of the same.

The leading feature of my design consists in a nozzle *a*, made cylindrical at the base at *a'* and having a tapering end, which nozzle is

erected on a spirally-corrugated cap *b*. The base of the nozzle *c* is made nearly as large in diameter as the diameter of the cap on which it is erected.

I claim—

The design for a cap and nozzle for atomizers, substantially as shown.

In testimony whereof I have signed my name to this specification in the presence of two subscribing witnesses.

ASAHEL M. SHURTLEFF.

Witnesses:

BERNICE J. NOYES,
FRED S. GREENLEAF.
